APTITUDE TESTER

Henry W. Wickes, Grosse Ile Township,
Wayne County, Mich.

Application May 29, 1942, Serial No. 445,019

3 Claims. (Cl. 35—12)

This invention relates to improvements in aptitude testers.

One object of this invention is to provide an improved aptitude tester for determining the aptitude of a person with respect to his ability or aptitude to become satisfactorily successful in the operation of mechanical devices such, for example, as operating an airplane or other mechanical device.

With the above and other objects in view, as will appear to those skilled in the art from the present disclosure, this invention may be understood by reference to the accompanying drawings, in which one way of carrying out the invention is shown for illustrative purposes.

Fig. 1 is a front elevation of an aptitude tester constructed in accordance with the present invention;

Fig. 2 is a top plan view of Fig. 1, with a chair for seating the person to be tested;

Fig. 3 is a side elevation of Fig. 2;

Figs. 4a and 4b when placed together form a schematic view illustrating the essentials of the construction and mode of operation of the aptitude tester; and

Fig. 5 is a plan view in the direction of arrow 5 of Fig. 4b, of a fragment of the contactor mechanism.

In the description and claims, the various parts and steps are identified by specific terms for convenience, but they are intended to be as generic in their application as the prior art will permit.

Referring to the drawings showing the particular form of the invention chosen for illustration after the person to be tested, hereinafter frequently referred to as the "subject," has been given an explanation as to the nature of the test he is to take on the aptitude tester 10, he will preferably be seated in a chair 11 before the aptitude tester 10. The headrest 12 can be adjusted about its frictionally-held pivot 13 on the bar 14 which is slideable in a carrier 15 pivoted to the bracket 16 secured to the top of the cabinet 17. A clamp 18 serves to frictionally lock the parts 14 and 15 in any desired adjusted position. The headrest 12 will preferably be adjusted so that the subject can comfortably hold his forehead near or against the front face 19 of the headrest 12 while he is being tested.

The subject will then preferably be given a short preliminary test which, for example, may be of one-minute length and may be hereinafter referred to as the warm-up period. After the warm-up period has been given, the real test is

given to the subject, the real test ordinarily being a longer period such, for example, as three minutes. The general procedure of operations with regard to the test will now be described as follows.

When certain switch mechanisms, all as more particularly hereinafter described, are operated by the person who is conducting the test, who may be hereinafter referred to as the "supervisor," several different types of visual-indicator means will be automatically actuated by the mechanism of the tester, which will engage the subject's attention and he is thereupon expected to do certain things in response to the actuation of at least most of these visual-indicator means, and the lapses of time which occur between the time that a given visual indicator-means goes on, until the subject takes the proper action in response thereto, is recorded upon one or the other of the two timer-devices 20 and 21. The timer-devices 20 and 21 are shown in Figs. 1, 2 and 3 of the drawings as being located upon the top of the cabinet 17 and as facing toward the rear of the machine away from the subject so he will not be able to read the time indications made by their respective hands or pointers 22 and 23. If desired, the timers 20 and 21 could be secured to the rear of the cabinet 17 or placed upon a separate table in the rear of the cabinet 30 out of sight of the subject.

When the mechanism is started in motion by the supervisor, one or another of the two red lights 24, 25 or one or another of the three green lights 26, 27, 28 or the white light 29 may be 35 flashed on by the mechanism, or the meter-hand 30 of the meter 31 may be caused to move from its normal central upright position to the right or to the left depending upon certain automatic electric contact mechanisms to be more fully 40 hereinabove described.

If one of the red lights 24 or 25 is flashed on, the subject is supposed to put it out by pushing straight in axially on the end of the red-light push-button switch 32 as quickly as he notices 45 one of the red lights go on, and the interval of delay between the time one of the red lights goes on and the time the subject puts it out, is recorded in seconds by the travel of the indicator-hands 22 of the lights-timer or time-recorder 20.

If one of the green lights 26, 27, 28 lights up, the subject is supposed to put it out by pressing axially upon the green-light push-button switch 33, thus breaking the circuit and causing certain 50 hereinafter described relay mechanism to act in a certain way so that when the switch 33 re-

turns to its normally closed position, the green light will not relight and again the time lapse between the time a green light went on and the time that the subject put it out by pushing upon the proper push-button switch 33 being added upon the lights-timer 20 by a further rotation of the indicator-hands 22.

If the meter-indicator hand 30 of the meter 31 moves clockwise, the subject is supposed to quickly rotate the meter-control knob 34 counterclockwise to just the proper degree to bring the meter-indicator hand 30 to the central or zero position within the dark area 35, and the time it has taken the subject to move the meter-hand back to zero will be indicated by the travel of the hands 23 of the meter-timer 21. Similarly, if the meter-hand 30 rotates counterclockwise, the subject brings it back to zero by rotating the control knob 34 clockwise. But if so desired, the device could be constructed so that if the mechanism moved the meter-hand clockwise, the control-knob would have to be moved clockwise to bring it back to zero, and if the mechanism moved the meter-hand counterclockwise, the control-knob would have to be moved counterclockwise to move the meter-hand back to zero. If the white light 29 flashes on, the subject is not expected to do anything about this, the white light merely being used as a distraction to test the subject's ability under distracting influences. After the white light has remained lighted a short while, it is put out automatically.

After the test has been concluded, the number of seconds that is indicated on the two timers 20 and 21 may be added up, and they give what may be called the score of the subject. Broadly speaking, the lower the score, within certain limitations, the better the aptitude indicated for the subject who has taken the test.

Referring to the schematic view illustrated in Figs. 4a and 4b placed together and read as one figure, the switches 36, 37, 38 and 39 are normally closed as shown, these switches being merely for use by a technician in testing parts of the apparatus, and so far as an understanding of the present invention is concerned, could be omitted. If so desired, they could be placed within the cabinet 17 so as only to be accessible from the rear thereof by opening the rear of the cabinet.

Ordinary 110-volt alternating current is used for part of the mechanism as, for example, by plugging in the plug-connector 40 into an ordinary alternating current supply, and direct current is used for other parts of the mechanism, as, for example, a 24-volt direct current by plugging in a plug-connector 41 to a suitable source of supply, which may, if desired, be obtained from the standard 110-volt alternating current by means of a suitable transformer and rectifier, all as is well known to those skilled in the art. The standard alternating current supply from the plug-connector 40 is indicated as being carried over wires that are shown by extra heavy black lines, while the direct current coming from the plug-connector 41 is carried over wires indicated by relatively-light lines, to thus aid the person reading the drawing in tracing the various circuits.

Prior to explaining in full detail the mode of operation of the device, a detail description will be given of certain of the more complicated sub-assemblies of the device. Thus, at the lower portion of Fig. 4b, the driving motor 42 through

gears 43 and 44 drives a main-shaft 45 indicated in broken lines, which main-shaft 45 extends through a hole 46 in a fixed insulation contactor-plate 47, and has rigidly secured on the shaft 45 to be rotatable therewith, a contactor-arm 48, an insulation meter-actuating cam 49, a gear 50 and a one-minute cam 51 of insulation. A three-minute cam 52 of insulation is mounted for free rotation on the shaft 45 and is driven from the gear 50 by the speed reduction gears 53 and 54 and shaft 55 to give the three-minute cam 52 a speed of rotation of one-third of the rate of rotation of the one-minute cam 51. It has been found satisfactory to have the warm-up period extend for a length of one minute, and the actual test period extend for a length of three minutes, although, of course, these periods can be of any length desired.

The contactor-arm 48 has a relatively-thin spring contact-portion or -member 56 adapted to be adjusted toward or from the contactor-plate 47 by an adjusting-screw 57 which is threaded through the rigid portion of the contactor-arm 48 and permits of adjusting the contact-member 56 to give a brief period of contact. When the contactor-arm 48 is rotated to a position to cause its contact-member 56 to contact with the fixed contact 58 carried by the contactor-plate 47, an electric circuit is closed through a coil 59 of the lock-in relay 60 which pulls up the contact-carrying bar 61 to close the switch-contacts 62 which results in the red light 25 being lighted. Even though the contact-member 56 now moves on beyond the contact 58 to thus break the current between them, the current through the coil 59 of the relay 60 continues to flow inasmuch as the contacts 62, when closed, serve to continue the current through the coil 59 as well as to continue the current through the red light 25. The current passing through the contacts 62 also passes through the spring-pressed red-light push-off switch 32. Inasmuch as the switch-contacts 63 of the lock-in relay 60 are also closed, they serve to cause current to pass through the lights-timer 20, to thus start the indicator-hands 22 on their time-indicating rotation. Thus, it will be seen that even though the contact-member 56 of the contactor-arm 48 has passed beyond and-out of electrical contact with the contact 58 to break the circuit therethrough, the electrical circuit through the red light 25, through the red light push-off button or switch 32, and through the lights-timer 20 continues until the circuit is temporarily broken by pushing on the spring-returned red-light push-off switch-button 32, whereupon the spring 64 of the lock-in relay 60 pulls the contact-carrying bar 61 to its lower or open position to thus break the circuits through contacts 62 and 63 of the relay 60 and thus put out the red light 25 and stop the rotation of the hands of the lights-timer 20. It will be observed from the electrical connections surrounding the contactor-plate 47 that when the contact-member 56 rotates sufficiently far to engage the other contacts 58, that the actions just described will again take place.

We will now assume that the contact-member 56 has rotated to come in contact with contact 65 on the contactor-plate 47, whereupon electric current will be supplied to the white light 29, but inasmuch as the white light 29 is provided merely for a distracting effect, no switch is provided for putting it out and it is not connected into any

timer-circuit, and therefore as soon as the contact-member 56 passes beyond and out of contact with the contact 65, the white light 29 goes out. It will be noted that there are two other white light-contacts 65 located at various places around the contactor-plate 47.

In a similar manner to that described concerning the contacts 58, when the circuit is closed through either of the two contacts 66 on the contactor-plate 47 by the contact-member 56, the green light 28, the lights-timer 20 and the green-light shut-off push button 33 will be brought into the circuit by means of a lock-in relay 67, all in a manner similar to that hereinbefore described concerning red light 25 and the lock-in relay 60. In a similar way, when the contact-member 56 rotates to a position to contact either of the two contacts 68, the circuit is closed through the red light 24, the lights-timer 20 and the red-light put-out switch 32 by a lock-in relay 69. And when the contact-member 56 engages any one of the three contacts 70, the green light 26, the lights-timer 20 and the green-light put-out switch 33 are energized by a lock-in relay 71. And when the contact-member 56 engages either of the two contacts 72, the green light 27, lights-timer 20 and the green-light put-out switch 33 are energized by a lock-in relay 73.

The mode of action of the meter-hand 30 of the meter 31, and the mode of steps to be taken in bringing the hand back to its central or zero position, and the portion of the apparatus which brings this about, will now be explained. The tapped resistor-coil 74 has exactly the same resistance as the infinitesimally-variable resistor-coil 75, and has its ends 76 and 77 respectively connected to the ends 78 and 79 of the resistor-coil 75 and these ends of the resistors 74 and 75 are connected to the direct-current power-source or connector-plug 41. A wire is connected to the tapped resistor 74 at its exact mid-point 80 to divide the tapped resistor 74 into two equal parts or sections indicated respectively by the brackets *a* and *b*, and includes the coil 81 of the sensitive relay 82, thence through the meter 31 and connects at 83 to the contactor-arm 84 carried by the meter control-knob 34, so that when the contactor-arm 84 is in its central or zero upright position as shown on the drawings, it divides the resistor 75 into two equal parts or sections indicated by the brackets *a'* and *b'* which respectively correspond to the parts *a* and *b* of the resistor 74. Thus, the central connection 80 to the middle of resistor 74 extending through the coil 81 of relay 82 through the meter 31 to the contactor 84, with the coil-sections *a*, *b*, *a'*, *b'*, in effect, constitutes a Wheatstone bridge. As long as the contactor-arm 84 is in the central upright or zero position shown in Fig. 4a, the resistances of the coil-sections *a*, *b*, *a'* and *b'* are so balanced that no current will flow in either direction from connection 80 of resistor 74 through the various parts described to the connection 83 of contactor-arm 84, and therefore the meter-hand 30 of the meter 31 will stand at its zero or central position as shown in Fig. 4a. No current is passing through the meter 31 because of the connection from 80 to 83 across exactly balanced resistances in accordance with the well known principle of the Wheatstone bridge.

If we now assume that the meter-actuating cam 49 at the lower part of Fig. 4b on shaft 45 is rotated to a position to cause the contact-carrying arm 85 to rise up on top of the high cam-section *c*, this closes the switch-contacts 86 to thereby

short circuit the portion of the tapped resistor 74 indicated by the bracket *c'*, to thus throw the resistances *a*, *b*, *a'* and *b'* out of their previous balance in accordance with the principles of the

- 5 Wheatstone bridge, whereupon direct current will flow in one direction through the coil 81 of the balanced-relay 82 to cause the switch-arm 87 of the relay 82 to swing into contact with one or the other of the contacts 88, 89, depending on the 10 direction of the current, to thus close the circuit through the coil 90 of the relay 91 to thus close the switch-contacts 92 to close the alternating-current power-circuit through the meter-timer 21. Also included in this circuit is the timer-switch 93 which of course, must be in closed position. If the timer-switch 93 is left open, then the power circuit will not be closed through the meter-timer 21, but this does not otherwise affect the circuit, and the current that flows through 15 the coil 81 and the meter 31 as a result of the unbalanced resistances of the resistors just described, will cause the meter-hand 30 to swing in the clockwise or counterclockwise direction, depending upon the direction of flow of the direct current. If the meter control-knob 34 is rotated 20 in the opposite direction to that in which the meter-hand 30 has been moved by the current passing through the meter, so as to move the contactor-arm 84 just the proper amount, the resistances *a*, *a'*, *b*, *b'* of the Wheatstone bridge construction are again put in balance so no current flows through the meter 31, and the meter-hand 30 is in consequence, caused to move back to the 25 zero area 35. And as there now is no current flowing through the coil 81 of the balanced relay 82, the switch-arm 87 thereof moves to the intermediate position shown in Fig. 4b with the consequence that the circuit to the coil 90 of the relay 91 is broken so that the spring 95 opens the 30 switch-contacts 92 to thus stop the meter-timer 21.

Now if it be assumed that the meter-actuating cam 49 has rotated to a position to permit the switch-contact-carrying arm 85 to drop down to the cam-surface *d*, the switch-contacts 86 will be opened to restore resistance-section *c'* back as an effective part of section *a* of resistor 74, and switch-contacts 94 will be closed, with the result that the portion of the resistor 74 indicated by the bracket *d'* will be short-circuited or cut out, to thus throw the Wheatstone bridge construction previously described out of balance, with the result that current will flow from the connection 80 of the resistor 74 through the coil 81 and the meter 31 to the connection 83 of the resistor 75 in the opposite direction, to thus close the circuit through the switch-arm 87 and one of the contacts 88, 89, to bring the meter-timer 21 into the alternating-current power-circuit, assuming the switch 93 to be closed, in a similar manner to that described heretofore. Inasmuch as the current now passes in the opposite direction from the direction it passed previously, it causes the meter-hand 30 to swing anticlockwise if, for example, it was swung clockwise previously, and in order to bring the meter-hand 31 back to its central or zero region indicated by the dark area 35, the meter control-knob 34 must be rotated clockwise to bring the contact-arm 84 to a position to balance the 55 various sections *a*, *a'*, *b*, *b'* of the Wheatstone construction, with the result that the current flowing through the meter will be reduced to substantially zero, to thus bring the meter-hand 30 back to its central or zero position and again 60 stop the meter-timer. In a similar manner to that described heretofore. Inasmuch as the current now passes in the opposite direction from the direction it passed previously, it causes the meter-hand 30 to swing anticlockwise if, for example, it was swung clockwise previously, and in order to bring the meter-hand 31 back to its central or zero region indicated by the dark area 35, the meter control-knob 34 must be rotated clockwise to bring the contact-arm 84 to a position to balance the 65 various sections *a*, *a'*, *b*, *b'* of the Wheatstone construction, with the result that the current flowing through the meter will be reduced to substantially zero, to thus bring the meter-hand 30 back to its central or zero position and again 70 stop the meter-timer. In a similar manner to that described heretofore. Inasmuch as the current now passes in the opposite direction from the direction it passed previously, it causes the meter-hand 30 to swing anticlockwise if, for example, it was swung clockwise previously, and in order to bring the meter-hand 31 back to its central or zero region indicated by the dark area 35, the meter control-knob 34 must be rotated clockwise to bring the contact-arm 84 to a position to balance the 75 various sections *a*, *a'*, *b*, *b'* of the Wheatstone construction, with the result that the current flowing through the meter will be reduced to substantially zero, to thus bring the meter-hand 30 back to its central or zero position and again stop the meter-timer.

Now when the meter-cam 49 rotates to a position to cause the switch-contact-carrying arm 85 to move up to the top of the cam-portion c^2 , the resistance-section d' is restored in the circuit of the resistor 74 and the resistance-section c' is cut out, thus so unbalancing the Wheatstone bridge construction as to throw the meter-hand 30 in the opposite or clockwise direction, and to bring it back to zero, the meter control-knob 34 is rotated in the manner heretofore described in the counterclockwise direction.

When the meter-cam 49 rotates further to permit the switch-arm 85 to drop to the intermediate-stage cam-surface 96, the switch-arm 85 moves to the position it occupies in Fig. 4b, in which the circuit is broken through both sets of switch-contacts 86 and 94, so that now the resistance-section c' of the resistor 74 is restored back in the circuit, so that now the resistor-circuit 74 includes its two full-length resistance-sections a and b , but inasmuch as the contactor-arm 84 had been previously moved to balance the circuit when the contactor-arm 85 was resting on the cam-surface c^2 to cut out the resistance-section c , it will now be necessary to rotate the meter control-knob 34 in the opposite direction to again bring the meter-hand 30 to its neutral position and halt the rotation of the hands of the meter-timer 21. And when the meter-cam 49 rotates further to the position to permit the switch-arm 85 to drop to the cam-surface d^2 , the resistance-section d' is short-circuited or cut out from the resistor 74 to thus unbalance the Wheatstone bridge construction and cause the meter-hand 30 to again be swung in the same direction as it had just previously been swung, so that in order to bring the meter-hand 30 back to its central position, the meter control-knob 34 must again be rotated in the same direction to bring the meter-hand back to its central or zero position, and again stop the rotation of the hands of the meter-timer 21. And this mode of action will continue as the meter-cam 49 continues to rotate and the switch-arm 85 moves to one or another of the various cam-surfaces of the meter-cam 49, the action of the meter-hand 30 and the necessary movement that must be given to the meter control-knob 34 to bring it back to zero, and the consequences of these various actions on various parts of the apparatus, will be understood from the description of the portion that has already hereinbefore been given.

Of course, various intervals of time which elapse between the times that the meter-hand 30 has been thrown off-center until it has been returned by the proper rotation and degree of rotation of the knob 34, and these are all totaled up by the successive rotational movements of the hands of the meter-timer 21. In a similar manner, when either a red light or a green light has been flashed on by the machine, and then has been put out by the subject, the intervals of time that the red and green lights have been burning before they have been put out by the subject pushing the proper switch push button, are also totaled up on the lights-timer 20.

It will now be assumed that it is desired to give the subject a warm-up period, which in the particular machine shown and described, amounts to a one-minute period, and thus while it could be any desired period, will be referred to in the description as a one-minute period, for convenience of description, it being assumed that the shaft 48 makes one complete revolution per minute and

that the shaft 45 and the parts mounted thereon are in the positions shown in Fig. 4b.

Assuming now that the subject is seated in the chair 11 before the aptitude tester 10, preferably with his forehead near or against the surface 19 of the headrest 12, the supervisor who is to conduct the test will first ordinarily have the timers-switch 93 open, inasmuch as it is not necessary to have the timers 20 and 21 record any time intervals, since the results of the warm-up periods are not intended to be recorded, inasmuch as the intention of the one-minute period is merely to familiarize the subject with the controls and manner of operation of the device as a preliminary to the actual test. The supervisor now sees that the selector-switch 97 is connected with the one-minute starting-switch 98 which preferably is a delayed-action switch or push button such that when it is pressed down to closed position, it returns to open position by action of the spring 99 only after a predetermined interval of time has elapsed, as a result of the dashpot 100 or any other suitable delayed-action mechanism. Thus, when the one-minute starting-switch 98 is depressed to closed position, it energizes the coil 101 of the motor-starting relay 102, with the result that the switch-arm 103 is pulled down to close the switch-contacts 104 to thus close the circuit through the electric motor 42.

As soon as the one-minute cam 51 is rotated sufficiently to cause the switch-arm 105 to rise up to the top of the cylindrical surface 106 of the cam 51, the switch-contacts 107 close the circuit through the coil 101 of the relay 102, so that even after the spring 99 has moved the one-minute starting-switch 98 up to open position, the motor 42 continues running until complete rotation of the cam 51 has taken place, when the switch-arm 105 will again drop down to its position in the notch 108, to thus open the contacts 107 and shut off the current to the coil 101 of the relay 102, whereupon the spring 109 will pull up to open the switch 104 and in consequence break the electric circuit to the motor 42 and thus cause the same to stop rotation which in consequence stops rotation of the shaft 45 and associated parts.

During this one-minute period which exists while the one-minute cam 46 is making one complete revolution, the contact-member 56 will be contacting at successive times one or another of the contacts 58, 65, 66, etc., on the contactor-plate 47 to light one or another of the red, green and white lights which will each be lighted a number of times during the single revolution of the one-minute cam 51 and the single revolution of the contact-member 56, and each time a red light lights, the subject is expected to push switch-button 32 to shut off the red light as quickly as he can, and each time that a green light lights, he is supposed to push the switch-button 33 to shut off the green light as quickly as he can. The white light, as has been previously described, does not require any action on his part, inasmuch as it automatically goes out after a certain interval of time, as hereinbefore explained. While the red, green and white lights are being lighted one at a time as a result of the rotation of the contact-member 56, the meter-cam 49 is also making one complete revolution and, depending upon whether a cam-surface c , d , c^2 , 96 , d^2 , or so forth engages the switch-arm 85, the meter-hand 30 will at intervals be swung clockwise and counterclockwise in a manner hereinbefore fully described,

and each time that the meter-hand 25 is moved by the mechanism from its center or zero position at the dark area 35, the subject is supposed to manipulate the meter control-knob 34 in a manner heretofore fully explained, to rotate it in the opposite direction to the direction in which the meter-hand has been moved by the mechanism, to bring the meter-hand back to its zero position. As previously mentioned, during this one-minute warm-up period, a timers-switch 93 has purposely been left open so as not to include the timers 20 and 21 in the circuit, as this warm-up period is not intended to make any timing test, but rather merely to give the subject a chance to familiarize himself with the mechanism and the steps necessary to take, in order to prepare him reasonably for the real three-minute test that will later be described. It will be noted that the spacing of the various fixed contacts carried by the contactor-plate 47 are at varied angles so that there will be no regular interval of time that the subject will be able to get used to, to expect something to happen, and this is also true of the lengths of the various cam-portions of the meter-cam 49, so that the time between successive throws of the meter-hand 30 will be at irregular intervals so as to be more or less unexpected when they occur. Also, the times when the meter-hand 30 are thrown by the mechanism in one direction or the other will preferably have an irregular period of relation with regard to the times that the lights are turned on by the mechanism, so that the subject will at all times find it necessary, if he wishes to make a good score, to keep his attention on both the lights and the meter, so as to be ready to take the proper action when either a red light is lighted or a green light is lighted or the meter-hand has been thrown by the mechanism in one direction or the other off from its center or zero position.

It will now be assumed that the shaft 45 and the cams 51 and 49 and the contact-member 56 have made one complete revolution, and when this has occurred, the switch-arm 105 which has been riding around the cylindrical surface 106 of the one-minute cam 51, will have dropped into the notch 108, thus breaking the circuit through the switch-contact 107 and in consequence breaking the power circuit to the motor 42, with the result that the motor 42 and all the rest of the mechanism stops.

A description will now be given of the actual three-minute test. As the preliminary or one-minute warm-up period occupied exactly one complete revolution of the one-minute cam 51, and as the three-minute cam 52 is driven through the gearing 50, 53, 55, 54, from its position shown in Fig. 4b at one-third the speed of the one-minute cam 51, the switch-arm 110 will be resting upon the outer cylindrical surface 111 at one-third revolution around from the notch 112 so that the circuit, so far as the switch-contacts 113 are concerned, is closed to the electric-drive motor 42, but the latter will not now run because the selector-switch 97 stands at the position it was connected to the one-minute starting-switch 98. The supervisor will now close the timers-switch 93 which will bring the timers 20 and 21 into the circuit, so that they will perform their timing function in the manner hereinbefore fully set forth.

Assuming now that the supervisor is ready to give the subject the regular three-minute test on the aptitude tester, he throws the selector-switch 97 into connection with the three-minute

starting-switch 116, which is a delayed-action switch similar to the one-minute starting-switch 98, and looks to see if the re-cycling pilot-light 114, which may, for example, be of an amber or other suitable color, has lighted as a result of his throwing the selector-switch as just stated. If the light 114 does not light, that is an indication that the three-minute cam 52 has not rotated enough to permit the switch-arm 110 to drop into the notch 112, since it would not have completed the rotation but would only have made one-third of a rotation from the position shown in Fig. 4b, since it travels one-third as fast as the one-minute cam 51, and therefore, as the switch-arm 110 is riding along the cylindrical surface 111 of the three-minute cam 52, the switch-contacts 113 will be held closed, thus causing the motor 42 to continue to rotate until the three-minute cam 52 has made one complete revolution, whereupon the switch-arm 110 will drop into the notch 112, thus breaking the power-circuit to the motor 42 and causing the motor and all the driving mechanism to come to a stop. But inasmuch as the breaking of the circuit through the contacts 113 has caused a breaking of the flow of current through the coil 101 of the relay 102, to thus break the circuit through the contacts 104 to the driving-motor 42 to thus stop the driving-motor, the spring 109 now pulls the switch-bar 103 up to close the switch-contacts 115 of the relay 102, thus closing the circuit through the recycling light 114 to thus light this light, which tells the supervisor that the switch-arm 110 is now resting in the notch 112 of the cam 52 and that the mechanism is therefore in proper position for the starting of the three-minute test period.

The supervisor now closes the three-minute starting-switch 116. The switch 116 remains in closed position for a sufficient length of time until the switch-arm 110 has ridden up out of a notch 112 onto the cylindrical surface 111 to thereupon close the circuit through the switch-contacts 113 to thus insure the maintaining of the power on the driving-motor 42, after which the delayed-action three-minute starting-switch 116 opens. Inasmuch as the drive-shaft 45 will now continue to be rotated by the drive-motor 42 for one complete revolution of the three-minute cam 52 and for three complete revolutions of the contactor-arm 43 and its contact-member 56, and of the meter-cam 49, the various red lights, green lights and white lights will be lighted, and the meter-hand 30 will be moved in opposite directions from the center or zero position, in a manner that has been hereinbefore fully described. During this three-minute test period, the various red, green and white lights are being lighted one at a time at intervals and the meter-hand 25 is being shifted to one side and the other at various times from its center or zero position at the darkened scale area 35, all as has been hereinbefore fully described. And each time a red light is lighted, for example, the lights-timer 20 is also brought into the circuit instantly and continues to have its indicator-hand rotate until the subject pushes on the push-out switch 32 to put out the red light that had been lighted, at which time the lights-timer 20 is disconnected from the circuit also, so that the lights-timer hands stop traveling until another red or green light is lighted and then the lights-timer 20 is again instantly brought into the circuit and its hands start to rotate on further to measure the time-interval that the light remains lighted until it also has been put out by operation of the

proper push-out switch, it being necessary for him to push the push-out switch 32 to put out a red light and to push the push-out switch 33 to put out a green light, all as hereinbefore described more fully.

And when the meter-hand 30 is swung in one direction away from its center or zero position the subject must rotate the control-knob 34 in the opposite direction to such an amount as will bring the meter-hand back to its zero position area, the period of time elapsing from the time that the meter-hand was thrown off zero by the mechanism until the subject has brought the meter-hand back to its proper position within the dark area 35 by proper manipulation of the control-knob 34, being recorded upon the meter-timer 21 each time. When the white light 24 is flashed on, there is nothing for the subject to do about it, but if he permits himself to be distracted or excited about it, he may not notice that the meter-hand 30 has been thrown off from its center position, thereby permitting the meter-hand to remain off its zero position a long time with the consequence that the meter-timer 21 will be recording a longer period which counts against the subject.

When the shaft 45 has made three complete revolutions, the switch-arm 110 will again drop into the notch 112 thus breaking the circuit through the switch-contacts 113 and thereupon stopping the motor 42 and causing the re-cycling pilot light 114 to light thereby telling the supervisor that the three-minute test period has been completed. Thereupon the supervisor lists down the number of seconds of total elapsed time it took the subject to put out the red and green lights that is totaled up on the lights-timer 20, and also notes down the total number of seconds that have been totaled up on the meter-timer 21 which indicates the total time that the meter-hand 30 has remained away from its zero or dark area 35.

The time shown by the two timers 20 and 21 can be added together to thus produce a total figure that can be regarded as the score made by the subject. Broadly speaking, the lower the score made by the subject, within certain limits, the higher the degree of aptitude of the subject.

Inasmuch as the main drive motor 42 and the motors (not shown) of the timers 20 and 21 are driven by alternating current, these motors can be synchronous electric motors.

While the aptitude tester of this invention has been primarily designed for testing prospective aviators, it could be used to test bus drivers, motormen, railroad engineers, truck drivers and so forth. One important point about the present invention is that it is purposely made so the mode of operation of the controls do not resemble those of any machine, so that the present invention provides a means for testing a person's aptitude without including in as part of the score he makes, that portion of his ability that is due to experience in the particular field that he may be tested for. The present aptitude tester tests the subject's time of reaction, ability to perform two operations simultaneously within certain limits of accuracy in each, dexterity of his arms, his memory, his angle of vision, his ability to carry out instructions with precision, color blindness, rate of absorption or accumulation of experience, ability to adjust controls to any pre-determined value, ability to use sound when available as an aid in making adjustments, fatigue (if test is continued sufficiently long) and

resistance to altitude (if the aptitude tester is placed in an evacuated chamber with the subject during the test).

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An aptitude tester including: support-means; first and second visual-indicator means on said support-means at spaced-apart locations at opposite sides of the center of said support-means, but within the possible angle of vision of a person located in front of said center of said support-means and intermediate said two spaced-apart visual-indicator means; said first visual-indicator means including lights of two different colors; on-actuator means for actuating said different colored lights and said second visual-indicator means to on positions; three off-actuator means adapted to be independently actuated by a person to independently actuate said different colored lights and said second visual-actuator means to off positions; and time-recording means for recording the lengths of time each color of said lights and said second visual-indicator means remain in on positions.

2. An aptitude tester including: support-means; first and second visual-indicator means on said support-means at spaced-apart locations at opposite sides of the center of said support-means, but within the possible angle of vision of a person located in front of said center of said support-means and intermediate said two spaced-apart visual-indicator means; head-positioning means located in front of and intermediate said two spaced-apart visual-indicator means for positioning a person's head; said first visual-indicator means including lights of two different colors; on-actuator means for actuating said different colored lights and said second visual-indicator means to on positions; three off-actuator means adapted to be independently actuated by a person to independently actuate said different colored lights and said second visual-actuator means to off positions; and time-recording means for recording the lengths of time each color of said lights and said second visual-indicator means remain in on positions.

3. An aptitude tester including: support-means; first and second visual-indicator means on said support-means at spaced-apart locations at opposite sides of the center of said support-means, but within the possible angle of vision of a person located in front of said center of said support-means and intermediate said two spaced-apart visual-indicator means; said first visual-indicator means including a group of at least four lights of two different colors; on-actuator means for actuating said different colored lights and said second visual-indicator means to on positions; three off-actuator means adapted to be independently actuated by a person to independently actuate said different colored lights and said second visual-actuator means to off positions; and time-recording means for recording the lengths of time each color of said lights and said second visual-indicator means remain in on positions.
